UNITED STATES PATENT OFFICE.

CHARLES COMSTOCK, OF RACINE, WISCONSIN.

SUPPORT FOR VEHICLE-BODIES.

SPECIFICATION forming part of Letters Patent No. 256,820, dated April 25, 1882.

Application filed December 7, 1881. (No model.)

To all whom it may concern:

Be it known that I, CHARLES COMSTOCK, of Racine, in the county of Racine, and in the State of Wisconsin, have invented certain new and useful Improvements in Supports for Vehicle-Bodies; and I do hereby declare that the following is a full, clear, and exact description thereof.

My invention relates to the manufacture of the supporting **A** parts of platform-wagons and the side-bar supports of buggies or other road-wagons; and it consists in certain peculiarities of construction, as will be more fully set forth hereinafter.

In the drawings, Figure 1 is a perspective of a continuous side bar embodying my invention. Fig. 2 is a like view of my invention applied to the **A** part of a platform-wagon, and Figs. 3 and 4 are detail sectional views.

A represents a side bar or **A** part for supporting vehicle-bodies, and is made of tubular iron, which in cross-section is either oblong, as shown in Fig. 3, or elliptical, as shown in Fig. 4. This is preferably made in one continuous piece bent into the required shape. This construction possesses the advantages of lightness, great strength, and cheapness. It can be readily

bent into the form desired, and when the support is to be adapted for platform-wagons the center bar, **B**, and brace **C** (shown in dotted lines in Fig. 2) can be readily and quickly clipped to the main frame or secured in various ways—as, for instance, a plug having forked ends to embrace and clip the narrow top or apex of the **A** part can be driven into the end of the bar **B**, if the latter is made of similar tubular iron. These details I regard as of small importance, the main feature being the tubular iron frame, oblong or elliptical in cross-section.

Having thus described my invention, what I claim as new, and desire to secure by Letters Patent, is—

In supports for vehicle-bodies, a continuous tubular iron frame bent into the required shape and elliptical or oblong in cross-section.

In testimony that I claim the foregoing I have hereunto set my hand this 23d day of November, 1881.

CHAS. COMSTOCK.
